US0D1030032S

(12) **United States Design Patent** (10) **Patent No.:** **US D1,030,032 S**
(45) **Date of Patent:** **** Jun. 4, 2024**

(54) **NEBULIZER COMPRESSOR**

(71) Applicant: **OMRON HEALTHCARE Co., Ltd.**,
Muko (JP)

(72) Inventors: **Asa Hirasawa**, Kyoto (JP); **Tsuyoshi Ogihara**, Kyoto (JP); **Kosuke Inoue**, Kyoto (JP); **Gen Suzuki**, Kamakura (JP); **Kengo Nishiyama**, Kyoto (JP)

(73) Assignee: **OMRON HEALTHCARE Co., Ltd.**, Kyoto (JP)

(**) Term: **15 Years**

(21) Appl. No.: **29/874,707**

(22) Filed: **Apr. 24, 2023**

(57) **CLAIM**

The ornamental design for a nebulizer compressor, as shown and described.

DESCRIPTION

FIG. 1 is a front, top, and right side perspective view of a first embodiment of a nebulizer compressor showing our new design;

FIG. 2 is a front, bottom, and left side perspective view thereof;

FIG. 3 is a front view thereof;

FIG. 4 is a rear view thereof;

FIG. 5 is a top view thereof;

FIG. 6 is a bottom view thereof;

FIG. 7 is a right side view thereof;

FIG. 8 is a left side view thereof;

FIG. 9 is a front, top, and right side perspective view of a second embodiment of a nebulizer compressor showing our design;

FIG. 10 is a front, bottom, and left side perspective view thereof;

FIG. 11 is a front view thereof;

FIG. 12 is a rear view thereof;

FIG. 13 is a top view thereof;

FIG. 14 is a bottom view thereof;

FIG. 15 is a right side view thereof; and,

(Continued)

FIG. 16 is a left side view thereof.

The dot-dash broken lines seen in the drawings represent a boundary and form no part of the claimed design. Features depicted within the boundary lines form no part of the claimed design.

1 Claim, 16 Drawing Sheets
